(57) CLAIM

The ornamental design for a combined sippy cup and handle base, as shown and described.

DESCRIPTION

FIG. 1 is a perspective view of the first embodiment of a combined sippy cup and handle base showing our new design;

FIG. 2 is a front view thereof, the rear view being identical;

FIG. 3 is a top view thereof;

FIG. 4 is a bottom view thereof;

FIG. 5 is a right side view thereof, the left side view being identical;

FIG. 6 is a perspective view of the second embodiment of a combined sippy cup and handle base;

FIG. 7 is a front view thereof;

FIG. 8 is a back view thereof;

FIG. 9 is a top view thereof;

FIG. 10 is a bottom view thereof;

FIG. 11 is a right side view thereof, the left side view being a minor image;

FIG. 12 is a perspective view of the third embodiment of a combined sippy cup and handle base;

FIG. 13 is a front view thereof;

FIG. 14 is a back view thereof;

FIG. 15 is a top view thereof;

FIG. 16 is a bottom view thereof;

FIG. 17 is a right side view thereof, the left side view being a mirror image;

FIG. 18 is a perspective view of a fourth embodiment thereof;

FIG. 19 is a front view thereof;

FIG. 20 is a back view thereof;

FIG. 21 is a top view thereof;

FIG. 22 is a bottom view thereof; and,

FIG. 23 is a right side view thereof, the left side view being a mirror image.

The broken lines illustrate portions of the combined sippy cup and handle base and form no part of the claimed design.
